(57) **CLAIM**

The ornamental design for a bracelet making machine as shown and described.

DESCRIPTION

FIG. 1 is a perspective view of a bracelet making machine showing my new design;
FIG. 2 is another perspective view thereof;
FIG. 3 is a front view thereof;
FIG. 4 is a back view thereof;
FIG. 5 is a left view thereof;
FIG. 6 is a right view thereof;
FIG. 7 is a top plan view thereof; and
FIG. 8 is bottom plan view thereof; and
FIG. 9 is a partial enlarged view of portion 9 in FIG. 1. The broken lines depict portions of the bracelet making machine and form no part of the claimed design. The dot-dash broken lines define the boundary of the enlarged view and form no part of the claimed design.
